THREADING DIE

Carl H. Ingwer, Elyria, Ohio, assignor to The
Ridge Tool Company, Elyria, Ohio

Application April 12, 1948, Serial No. 20,379

2 Claims. (Cl. 10—120)

1

This invention relates to improvements in threading dies and more particularly to an improved die head such as is used for threading pipes, having a novel arrangement for holding the thread cutting chasers. The invention is an improvement over the die shown in my Patent No. 2,242,954, of May 20, 1941.

Previously, die heads have had complicated mechanism for holding the chasers; in some cases requiring especially designed chasers. In addition, in the construction of the various parts, it was often required that special machinery be used to finish each part. In other cases, complicated castings or die castings were required. It often happened that because of the peculiarity of the manufacturing processes required, it was virtually impossible to use any material other than the specific one for which the piece was designed.

By the present invention, it is possible to manufacture a die stock without the use of expensive and not-so-strong die castings and without use of complicated and expensive machining operations. In addition, by my invention, the need for complicated cores to make the castings is eliminated, and those parts which must have additional strength are so designed as to lend themselves readily to a forging process.

The construction is such as to allow the various parts to be machined in a simple and easy manner without special equipment. Furthermore, the design enables the chassis to be held with great rigidity while enabling them to be replaced easily and quickly as well as revised, should the occasion demand it.

All of these advantages and other advantages, as well as the economies in manufacture, will be more apparent from the description of the invention which is illustrated in the accompanying drawings.

Fig. 1 is a side view showing the die stock completely assembled;

Fig. 2 is a view of the assembled die stock looking at its face;

Fig. 3 is an exploded section of the assembly showing each piece in its proper relation to the others;

Fig. 4 is a view of the underside of the face plate showing the positioning and strengthening lugs;

Fig. 5 is a top view of the die body;

Fig. 6 is a view of another face plate for a larger die showing the post and chaser engaging lugs; and

Fig. 7 is a fragmentary elevational view showing the chip discharge opening in the die.

Throughout the drawings like parts are designated by like reference characters.

In general, the die comprises a body which has a sleeve or barrel adapted for connection

to a handle which may be of the ratchet type. The thread cutting chasers are supported by the body and are held in place by a face plate which positions them and clamps them in the body.

More specifically, the body 10 comprises a sleeve part 11 for engagement with a ratchet wrench and has a base 12 which is ring shaped. The base supports four post-like members 13 which extend parallel to the axis of the sleeve and are equally spaced around the base. This body 10 may be formed of a casting, although it is not limited to such formation with the external surfaces machined together with the pipe guiding bore 14. This machining is not necessary but lends a finished appearance to the tool. The end faces 15 of the posts 13 are finished normal to the guiding bore 14. Radially and longitudinally extending channels 16, for holding the thread cutting chasers, are then machined through the posts 13 in diametrically opposed relationship by milling across the end of the body. Parallel to these channels, lug-engaging shoulders 17 are machined on the posts 13. The side walls of each channel 16 are parallel to each other and at a fixed distance apart and are also parallel to the sides of the shoulders 17. The bottom of each channel 16 is square with the side walls and with the guiding bore 14 in order to provide for the proper alignment of the thread cutting chasers 18 which are carried therein. Threaded holes 19 are provided in the posts 13 to receive screws as hereafter described.

The thread cutting chasers 18, Fig. 3, are provided with parallel sides and a top and bottom at right angles to the sides for engagement with the sides and bottom of the channel 16. Thread cutting teeth 20, which may be of conventional design, are provided on one end of the chaser. Grooves 21 of trapezoidal cross section having 40 a perpendicular side toward the teeth and in a fixed position with respect to the teeth, are machined transversely in the top and bottom of each chaser.

The face plate 22, which may be a forging, is generally ring shaped having an outer diameter 41 substantially the same as the periphery of the base 12 of the body 10. The inner diameter 42 is such as to provide sufficient clearance with the material on which threads are being cut. Countersunk holes 23 are provided in the face plate for reception of oval head machine screws 24 which extend therethrough and are threaded into the tapped holes 19 in the posts 13 to hold the plate 22 in place.

The side of the plate adjacent to the body 10 is provided with four lugs 25 equally spaced around the ring and located at a predetermined distance from the center line of the face plate 22. These lugs 25 are shaped to fit into the 60 grooves or notches 21 in the chasers 18 and are

adapted to hold the chasers in a fixed position in the body 10. Also on this side of the face plate are eight post engaging lugs 26 which are spaced to engage the shoulders 17 cut into the posts 13. These lugs serve to support and strengthen the posts against the side thrust of the chasers 18 by holding each of the posts in a fixed relation to each other and preventing the ends of the post from spreading apart.

All these lugs may be forged roughly on the face plate 22 and can then be easily machined to dimension. For instance, there could be a boss, the outlines of which are indicated by the dotted lines 40 in Fig. 4 and this boss machined to provide the lugs. The manner in which this is done is best shown in connection with Fig. 6 which is a view of a face plate for a larger die than that shown in the other figures. The manner of construction is, however, substantially the same for either of the plates.

It will be noted that the inner surface 25a of the lugs 25 is on a line with the surfaces 26a of the lugs 26, which line is a chord across the plate. This enables the plate to be manufactured by a forging process wherein the plate is formed with four solid bosses of a contour as best shown in Fig. 6 by the lines 30.

At this time the boss 25a is roughly formed, having the outer slanting surface 25b, the space 25c, and 25d on opposite sides being nearly flush with the surface of the plate outside of the lug.

Subsequently to the forging operation, the lugs 25 and 26 are formed by a few simple machining operations. This may be effected by milling the channels 31 transversely across the plane as indicated by the dot dash lines 32. The channels 33 are likewise milled by a cutter as indicated by the dot dash lines 34.

It will be noted that the milling operation which forms the faces 26a and 25a on the lugs 26 and 25 respectively may be such as shown in Fig. 4 that all of the rough lug 40 is removed from these surfaces to the center hole 42. It has been found that this leaves the lugs 26 sufficiently large and strong to provide the proper support for the posts.

In the case of the face plate of Fig. 6, however, where the die is to be used for threading larger pipe, it may be desirable to provide a larger lug 26. Since the milling operation for the groove 34 is primarily to determine the exact position of the face 25a on the lug 25, the milling cutter in this instance may be narrower and parts of the lug 26 will be left on each side of the slot 33, thus providing a broader surface for engaging the seats or shoulders 17 of the posts. Also during the forging operation, the lugs 30, Fig. 6, are formed with fillets 35 which provide additional reinforcement for the lugs as well as providing a more symmetrical contour for the chip relieving openings between the posts on the assembled die as best shown in Fig. 7.

The assembly of the device can be easily accomplished by placing the thread cutting chasers 18 in the channels 16 with the teeth 20 inward. The face plate 22 is then placed over the body with the positioning lugs 25 engaging the grooves 21 in the chasers 18. The supporting lugs 26 will engage the shoulders 17 on the posts 13. The screws 24 are then inserted through the holes 23 and screwed into the tapped holes 19 and screwed down securely. The chasers are then

securely held in position and the posts 13 are supported in fixed relationship to each other.

It will be seen that all machining of the channels, shoulders, and lugs consists of simple operations, primarily straight cuts across either the body or the face plate requiring no special tools.

It should also be noted that because of the manner in which the face plate engages the posts (the lugs being on each side of the post) that great strength is given to the posts without the need of the bridging portions as shown in the previously mentioned patent. This facilitates the ease with which the parts may be made, eliminating expensive cores previously needed.

Although the device is shown with four chasers, it is obvious that the number of chasers may be varied without departing from the spirit or the scope of my invention. Still other departures from the structure shown will be apparent to those skilled in the art which may be made without departing from the spirit of the invention.

I claim:

1. A threading die including a body having a central work-receiving opening therein, a plurality of posts on said body extending co-axially around the work receiving opening, said posts having diametrically opposed chaser slots and being formed with shoulders on the outer surfaces in spaced parallel relation to said slots, chasers substantially filling said slots and each having a lateral notch in at least one edge thereof and thread cutting teeth along one end, each of said notches having one face substantially parallel to the axis of the body, means to hold said chasers rigidly in said slots and to hold the posts against spreading comprising a face plate having lug means, each of said lug means having a flat face; in positioning engagement with said one face in the notch of each of said chasers to positively determine the radial position of said chasers in said slots and having lug means in engagement with said shoulders thereby supporting said posts on both sides thereof, and means to hold said plate to said posts.

2. A threading die including a body having a central work-receiving opening therein, a plurality of posts on said body extending coaxially around the work receiving opening, said posts having diametrically opposed chaser slots and being formed with shoulders in spaced parallel relation to said slots and on opposite sides thereof, chasers substantially filling said slots each chaser having a notch in at least one edge thereof and thread cutting teeth along one end, means to hold said chasers rigidly in said slots and to hold the posts against spreading comprising a face plate having lug means in positioning engagement in the notches of said chasers in said slots and having lug means in engagement with said shoulders on opposite sides of said posts, and means to hold said plate to said posts.
